UNITED STATES PATENT OFFICE.

JOSEPH C. ELDER, OF CARTHAGE, ILLINOIS.

DESIGN FOR A WIRE-TIGHTENER.

SPECIFICATION forming part of Design No. 34,630, dated June 4, 1901.

Application filed February 23, 1901. Serial No. 48,622. Term of patent 7 years.

To all whom it may concern:

Be it known that I, JOSEPH C. ELDER, a citizen of the United States, residing at Carthage, in the county of Hancock and State of Illinois, have invented and produced a new and original Design for a Wire-Tightener, of which the following is a specification.

This invention relates to a design for a wire-tightener for engaging fence-wires and the like to twist the same to take up slack, and the essential feature resides in the design illustrated in the accompanying drawing, wherein a perspective view of a wire-tightener embodying the design is shown.

The design is characterized by a straight shank 1, having a loop 2 at a right angle thereto at one extremity, the said loop being broad at its lower portion and having the sides there-

of converged toward the upper open portion thereof, a curved terminal 3 continuing from the upper portion of the loop and disposed approximately in the same plane as the shank. The opposite extremity of the shank is formed with a short length of an Archimedean spiral 4, which is consequently tubular.

Having thus described the invention, what is claimed as new is—

The design for a wire-tightener, herein shown and described.

In testimony that I claim the foregoing as my own I have hereto affixed my signature in the presence of two witnesses.

JOSEPH C. ELDER.
